UNITED STATES PATENT OFFICE.

MORRIS KURTZON, OF CHICAGO, ILLINOIS.

COMBINED PUSH-BUTTON LATCH AND LOCK.

1,186,803.

Specification of Letters Patent. Patented June 13, 1916.

Application filed November 2, 1914. Serial No. 869,752.

To all whom it may concern:

Be it known that I, MORRIS KURTZON, a citizen of the United States, residing at Chicago, in the county of Cook and State 5 of Illinois, have invented certain new and useful Improvements in Combined Push-Button Latches and Locks, of which the following is a specification.

My invention relates to push button 10 latches and more particularly the type employed on cabinet doors, drawers and the like, although after an understanding of the construction is had it will be obvious to others skilled in the art to which it pertains 15 that the principle thereof may be well adapted to latches for other styles of doors, windows, gates, etc.

The primary object of my invention is to 20 construct a novel easily operated, and effective latch and to provide the same with means whereby it may be locked, the former structure operated by a push button and the latter by a removable key inserted in said push button.

Another object is to construct the device 25 in as simple a manner as possible in order to reduce the cost of manufacture to a minimum and at the same time prevent the latch getting out of order.

Other objects will be obvious from the 30 following description wherein I have described a preferred form of latch and lock, the construction of which is illustrated in the accompanying drawings forming a part 35 of this specification.

In the drawing similar reference characters indicate the same parts in the various figures.

Figure 1 is a vertical sectional view of 40 my improved push-button latch and lock taken centrally of the button and showing the button pushed inward. Fig. 2 is a transverse section thereof taken at right angles to Fig. 1 to better illustrate the construction 45 of the locking mechanism.

Referring to the drawings, A represents 50 a suitable box-like housing or casing that incloses the mechanism of the latch, one of the walls whereof is removed and the opening formed thereby closed by a suitable plate B provided with lateral tubular embossment or barrel C. This embossment is of a length sufficient to extend through 55 the panel, stile or other strip of material to which the latch may be secured in any suitable manner. A pawl or latch 5 of substan-

tially triangular shape is pivotally mounted upon a transverse pin 6 extending through the side walls of the casing, and said latch when in normal position has its wedged or inclined side projected through an elongated opening or slot 7 in the adjacent wall of the casing. A small spring 8 is preferably coiled around the pin 6 and has its free end extended laterally away from said pin to a suitable lug 9 projecting laterally from said latch, the action of which spring being to keep the latch normally pressed outwardly through slot 7 as seen in Fig. 1 of the drawings. The body of the latch is preferably 70 slotted longitudinally to form bifurcations 10 and said bifurcations are connected by a suitable cross-pin 11 passing transversely through them.

Pivotally mounted upon a transverse pin 75 12 extending across the casing is a suitable sickle-shaped lever 13 the curved arm of which passes between the bifurcations in the latch-body and normally bears against the cross-pin 11 so that the rocking of said lever will draw or move the latch into the casing as shown in Fig. 1 of the drawings. The opposite end of said lever is preferably deflected at a slight angle to said sickle-shaped arm and has pivoted to its outer end 80 a suitable socket 14 the bifurcated rear portion of which straddles said lever and is secured thereto by a pin 15. In order to actuate lever 13 a suitable plunger 16 is mounted in the barrel C of the front plate. 90 The inner end of this plunger is provided with a substantially arrow-shaped head 17 that is adapted to be seated in the socket 14 on the operating lever while its outer end is preferably reduced in diameter to form a 95 push-button 18 that passes through the restricted opening in the outer end of the barrel, which opening is formed by bending the end edge of said barrel inwardly to form an internal annular flange 19. Thus, 100 it will be apparent that when the push-button end of the plunger is moved inwardly the arrow-head inner end seated in socket 14 will move lever 13 upon its fulcrum and cause the latch body to be withdrawn or 105 moved into the casing until its inclined surface lies flush with the adjacent surface of the casing.

In order to lock the latch and prevent its being operated by the push-button plunger 110 I prefer to cut a key-slot 20 longitudinally in said plunger into which a suitable re-

cessed or tumbler key is adapted to be inserted. A portion of the shank of the key is adapted to engage a slide plate 22 that is irregular shaped and provided with longitudinally alining slots 23 and 24 into which project short pins 25 and 26 arising from an offset shelf *a* of the casing in order to guide the longitudinal movement of said plate. An arc-shaped recess 27 is made in the edge of the plate adjacent the key that has a lateral offset 28 adapted to be engaged by the key so as to move the plate to the position indicated in dotted lines in Fig. 2 of the drawings. The locking plate 29 is superimposed upon said slide plate 22 and conforms somewhat with the irregular contour thereof. This locking plate is pivotally mounted at one corner upon the guide pin 25 before mentioned so as to permit its diagonally opposite corner being moved into the path of the latch body as indicated in dotted lines in Fig. 2 of the drawings and in order to keep said locking plate normally pressed in this direction I interpose a suitable spring 30 between its edge and the adjacent wall of the casing, one end of said spring entering a slot 31 cut in the edge of said plate substantially as shown. One edge of the locking plate has irregularly curved recess 32 formed therein into which a pin or lug 33 rising from the face of the slide plate projects for this purpose to retain said locking plate in a position removed from or out of the path of the latch, and which, when said slide plate 22 is moved longitudinally by the shank of the key, is adapted to be moved out of said recess and thus permit the locking plate 29 to swing upon its pivot until its corner edge has moved into the path of said latch and prevent the movement of the latter. I have found it desirable to make an inclined or wedge-shaped engaging surface or edge 34 on the locking plate at one side of recess 32 so that when the slide plate is moved to unlock the upper or locking plate 29 the pin 33 will be readily guided to said recess by moving said locking plate laterally out of the path of the latch.

While I have illustrated and described certain specific instrumentalities for carrying out my invention it will of course be obvious that modifications thereof are possible without departing from the spirit of my invention. I therefore desire it understood

that all obvious changes or refinements of the structure described and illustrated are contemplated within the scope of the appended claims.

What I claim as new and desire to secure by Letters Patent is:

1. A latch comprising a pivoted latch member and means for actuating the same consisting of a lever one end of which engages said latch member, a socket carried by said lever, and a plunger the inner end of which seats in said socket. 65

2. A latch comprising a pivoted latch member and means for actuating the same consisting of a lever one end of which engages said latch member, a socket pivotally carried on the opposite end of said lever, and a plunger the inner end of which seats in said socket. 70

3. A latch comprising a pivoted latch member and means for actuating the same consisting of a lever one end of which engages said latch member, a socket pivotally carried on the opposite end of said lever, and a plunger the inner end of which seats in said socket, and a locking device movable into and out of the path of said latch member. 75 80

4. A latch comprising a pivoted latch member and means for actuating the same consisting of a lever one end of which engages said latch member, a socket carried by said lever, and a plunger the inner end of which seats in said socket and a locking device movable into and out of the path of said latch member. 85 90

5. A latch comprising a pivoted dog, pivotal means for actuating the dog, one end of which engages the same, a bearing pivoted to the opposite end of said pivotal means, a plunger adapted to seat therein, and means for controlling the movement of said plunger. 95

6. A latch comprising a pivoted latch member, pivoted means for actuating said member one end of which engages the same, a plunger adapted to engage the opposite end of said pivoted means, and a locking device comprising a spring pressed pawl adapted to engage said plunger and prevent the movement thereof. 100 105

MORRIS KURTZON.
